ATTORNEY

UNITED STATES PATENT OFFICE.

EMIL C. WENTE, OF WAVERLY, IOWA.

TILE FORK.

Application filed September 10, 1926. Serial No. 134,747.

This invention relates to certain novel improvements in tile forks and has for its principal object the provision of an improved construction of this character which will be highly efficient in use and economical in manufacture.

Among the several objects of the invention is the provision of a tile fork which may be expeditiously handled for the removal of cell type tiles from a pile of tiles or from a tile wall to be wrecked.

Heretofore it has been the ordinary custom for the workmen to lift the tile or remove the tile from the tile wall or fitted place as a part of the tile wall construction by the use of the hands. The disadvantage resulting in this method resulted in the workmen bruising their hands and incurring considerable loss in labor. By the use of my improved tile fork it will be hereinafter understood that the workman can operate on the tile without touching the same with his hands and the tile fork being easy to handle abolishes excessive loss of labor.

26 Other objects will appear hereinafter.

The invention consists in the novel combination and arrangement of parts to be hereinafter described and claimed.

The invention will be best understood by reference to the accompanying drawing showing the preferred form of construction and in which:

Fig. 1 is an elevational view of the invention,

35 Fig. 2 is a sectional detail view taken substantially on line 2—2 of Fig. 1, and

Fig. 3 is a sectional detail view taken substantially on line 3—3 of Fig. 1.

Referring to the drawing I illustrate the preferred form of construction as comprising a shank 10 carrying at one end portion a handle 11. This handle 11 may be of any approved construction which includes a sleeve 12 secured to the shank 10 through the medium of a pin 13. The opposite end portion 14 of the shank 10 has secured on the bottom side 15 thereof a bracket 16 defining a bearing sleeve 17. Secured to the opposite side 18 of the shank at the end portion 14 is a plate 19, said plate and said bracket being connected to the shank 10 by a bolt 20. The plate 19 defines an extended portion 21 which extends beyond the side 15 of the

shank 10 and forwardly of the end portion 14 and this extended portion 21 defines an opening 22.

A gripping finger 23 is defined by a wire member which is bent substantially U-shaped as best shown in Fig. 1. The limb portions 24 of the wire member are looped to define bearings 25 disposed oppositely with respect to each other and inwardly of the bight portion 26 of this gripping finger. The bight portion 26 is received by the bearing sleeve 17 for pivotal movement. Carried by the limb portions 24 and having opposite end portions 27 received in the bearings 25 is a pintle 28. This pintle 28 loosely carries a sleeve 29 connected by solder or the like to a loop 32 formed intermediate the end portions of a gripping finger 31. This gripping finger 31 is disposed between the limb portions 24. The end portion 33 of the gripping finger 31 is bent back upon itself through the opening 22 to define a hook 22'.

A hand gripping wire 34 is defined by a wire which is bent substantially U-shaped with its end portions 35 looped around the pintle 28 between the sleeve 29 and the bearings 25.

In use the operator firmly grasps the handle 11 with one hand and firmly holds the hand gripping wire 34 in his other hand. He now pulls the hand gripping wire in a direction to pivot the gripping finger 24 about its connection with the bearing sleeve 17. As this gripping finger pivots in this direction the extended portion 21 bears down upon the end portion 33 of the gripping finger 31 and pivots this gripping finger and the sleeve 29 about the pintle 28 thereby disposing the gripping finger in an upward spaced position with respect to the limb portions 24. The fork in this position is now placed into engagement with the tile, with the wall portion of the tile disposed above the limb portions 24 and beneath the gripping finger 31. A hand gripping wire 34 is now released and the operator now lifts the shank 10 upwardly to cause the gripping fingers 24 and 31 to clamp against the wall portion of the tile. This clamping action takes place by reason of the fact that when the handle is lifted upwardly the weight of the tile will pivot the gripping fingers 24 in its sleeve 17 and the greater

the weight of the tile the tighter the clamping relation between the gripping finger becomes.

From the above description it is manifest that I provide a tile fork which can be expeditiously operated and which will be highly efficient in the art.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

The invention having been set forth, what I claim as new and desire to secure by Letters Patent is:

1. A tile fork comprising a shank, a gripping finger, pivotally connected to the shank, a second gripping finger cooperating with the first mentioned gripping finger for clamping a tile between said first mentioned gripping finger and said second mentioned gripping finger, means pivotally connecting the second mentioned gripping finger to the first mentioned gripping finger, and means operatively connecting said second mentioned gripping finger to said shank whereby when said shank is supported in the hands of an operator the gripping fingers will be caused to move toward each other into clamping relation with respect to the article disposed between the gripping fingers.

2. A tile fork comprising a shank, a bracket associated with the shank at one end thereof and defining a bearing sleeve, a gripping finger formed from a wire member bent substantially U shaped and having its bight portion pivotally associated with the bearing sleeve, a pintle carried by the clamping finger forwardly of the bight portion, a gripping finger pivotally connected to the first mentioned gripping finger by said pintle, said second mentioned gripping finger defining an extended portion having an end portion bent to define a hook, and a member associated with said end portion of the shank and defining an extended portion provided with an opening for the passage of said end portion of the second mentioned gripping finger.

3. A tile fork comprising a shank, a bracket

associated with the shank at one end thereof and defining a bearing sleeve, a gripping finger formed from a wire member bent substantially U shaped and having its bight portion pivotally associated with the bearing sleeve, a pintle carried by the clamping finger forwardly of the bight portion, a gripping finger pivotally connected to the first mentioned gripping finger by said pintle, said second mentioned gripping finger defining an extended portion having an end portion bent to define a hook, and a member associated with said end portion of the shank and defining an extended portion provided with an opening for the passage of said end portion of the second mentioned gripping finger, and a hand gripping member having opposite end portions curled around said pintle, said hand gripping member being adapted to be grasped by the hand of the operator to pivot the first mentioned gripping finger relative to the second mentioned gripping finger to dispose the gripping fingers in position for receiving the wall portion of a tile to be lifted by said tile fork.

4. A tile fork comprising a shank, a bracket associated with the shank at one end thereof and defining a bearing sleeve, a gripping finger formed from a wire member bent substantially U shaped and having its bight portion pivotally associated with the bearing sleeve, a pintle carried by the clamping finger forwardly of the bight portion, a gripping finger pivotally connected to the first mentioned gripping finger by said pintle, said second mentioned gripping finger defining an extended portion having an end portion bent to define a hook, and a member associated with said end portion of the shank and defining an extended portion provided with an opening for the passage of said end portion of the second mentioned gripping finger, and a hand gripping member bent substantially U-shaped having opposite end portions curled around said pintle, said hand gripping member being adapted to be grasped by the hand of the operator to pivot the first mentioned gripping finger relative to the second mentioned gripping finger to dispose the gripping fingers in position for receiving the wall portion of a tile to be lifted by said tile fork.

In testimony whereof I affix my signature.

EMIL C. WENTE.
